UNITED STATES PATENT OFFICE.

CHARLES E. NUTTING, OF HOPEDALE, MASSACHUSETTS, ASSIGNOR TO DRAPER CORPORATION, OF HOPEDALE, MASSACHUSETTS, A CORPORATION OF MAINE.

LOOM-FROG.

1,322,605.

Specification of Letters Patent. Patented Nov. 25, 1919.

Application filed June 13, 1919. Serial No. 303,964.

To all whom it may concern:

Be it known that I, CHARLES E. NUTTING, a citizen of the United States, and resident of Hopedale, county of Worcester, State of Massachusetts, and whose post-office address is Hopedale, Massachusetts, have invented an Improvement in Loom-Frogs, of which the following description, in connection with the accompanying drawing, is a specification, like characters on the drawing representing like parts.

This invention relates to a loom frog such as employed in the protector mechanism for looms.

15 The object of the invention is to provide a construction in which a helical wire compression spring, and preferably a pair of such springs, is provided to take up the blow on the loom frog when the protector mechanism acts, thus eliminating the use 20 of rubber buffers which deteriorate, wear and are liable to get out of order.

25 The object of the invention is also to provide a loom frog in which the parts including the springs may be readily assembled and in which the correct position of the springs is insured at all times.

30 These and other objects of the invention will appear more fully from the accompanying description and drawings, and will be particularly pointed out in the claims.

In the drawings—

35 Figure 1 is a view in side elevation of a portion of a loom showing the frog with the invention embodied therein.

Fig. 2 is an enlarged detail taken in cross section on the line 2/2 of Fig. 3.

40 Fig. 3 is a side elevation of a portion of a loom frame showing the frog in position, and with the parts partially in vertical section to expose the springs.

45 Fig. 4 is a view similar to Fig. 3 showing the frog in the position to which it is moved upon the actuation of the protector mechanism.

Fig. 5 is a top plan view partially broken away of the construction shown in Fig. 3.

50 The protector mechanism for a loom by means of which the loom is stopped when a shuttle fails to be boxed or is improperly boxed is a well known and common mechanism and in a simple form is illustrated in the patent to Draper No. 911,219, granted Feb. 2, 1909.

55 This protector mechanism usually in-

cludes at one or both sides of the loom a part which is known as a frog and which is slidably mounted upon the loom frame. In case the shuttle fails to box, or is improperly boxed at the end of the lay, certain mechanism, which it is unnecessary to illustrate or describe, is brought into play which causes a dagger attached to the lay to drop into the path of a projection on the top of the frog so that, as the lay beats up, 60 the dagger strikes the frog and carries it forward thus actuating mechanism which causes the loom to knock off or stop. This mechanism is of a well known and familiar type and as the present invention relates to 65 but a single feature it need not further be described.

In the preferred construction illustrated, the frame 1 at one side of the loom is shown as provided with the usual shipper 2 standing in the position in which it occupies when the loom is running. When the shipper is thrown rearwardly it will swing laterally into the recess 3 and through suitable connections shift the belt from the fast to 70 the idle pulley or otherwise act to stop the loom.

A horizontal portion 4 of the loom frame serves as a frog support upon which is slidably mounted the frog 5. This frog is recessed at 6 opposite to the support 4 and is guided in its sliding movement in any suitable manner. For that purpose the forward end of the frog is shown as bifurcated at 7 and straddling the upright portion 8 of the 90 loom frame, while at its rear end it is again bifurcated at 9 and fits over a block 10 secured by a bolt 11 to the loom frame.

A thrust member 12 is seated in the recess 6 of the frog on the support 4 and abuts 95 against some fixed portion of the loom, such as the projection 13 from the support 4. This thrust member is shown as having a flat base resting on the support and an up-standing flange 14. Projecting from this 100 flange 14 of the thrust member are a pair of centering conically pointed projections 15.

A pair of helical wire compression springs 16 are located in the recess 6 of the frog, and each of the springs fits at one end over 105 one of the centering points 15 and abuts against the thrust member 12 and at the opposite end abuts against the inner surface or wall 17 of the frog. The centering points thus serve to position the helical springs and 110

hold them in place. In addition, the frog is provided with a separating rib 18 depending from the wall of the recess opposite the support and between the spring 16 and this rib further acts to position and support the springs.

It will thus be seen that a very strong and simple construction is provided, the parts of which may be readily assembled in position on the loom, and one in which a heavy compression may be readily provided. The springs are protected by the frog and will last indefinitely.

In the operation of the protector mechanism the improper boxing of the shuttle, or the failure of the shuttle to box, causes the dagger 19 to drop into the path of the frog. As the lay beats up, the dagger strikes against a hardened plate, not shown, supported by the shoulder 20 and moves the frog forward by compressing the springs 16. This movement of the frog through suitable means not shown actuates the shipper to stop the loom. At the conclusion of the beat up the springs 16 act to return the frog to normal position.

Having thus described my invention what I claim as new and desire to secure by Letters Patent is—

1. A protector mechanism for looms comprising, a frog support, a frog recessed opposite to, and slidingly mounted upon, the support, a thrust member in said recess seated on said support and provided with a pair of centering points, and a pair of helical

wire compression springs in said recess, each spring fitting at one end over one of said centering points and abutting the thrust member and at the opposite end abutting the frog.

2. A protector mechanism for looms comprising the construction defined in claim 1 together with a separating rib depending from the wall of the recess in the frog opposite the support and between the springs. 40 45

3. A protector mechanism for looms comprising a frog support, a frog recessed opposite to, and slidingly mounted upon, the support, a thrust member in said recess seated on said support and provided with a centering point, and a helical wire compression spring concealed between the frog and the support in said recess fitting at one end over said centering point and abutting the thrust member and at the opposite end abutting the frog. 50 55

4. A protector mechanism for looms comprising a frog support, a frog recessed opposite to, and slidingly mounted upon, the support, a thrust member in said recess seated on said support, a pair of helical wire compression springs in said recess, each spring abutting at one end said thrust member and at the opposite end said frog, and means for maintaining the said springs 60 65 separated.

In testimony whereof I have signed my name to this specification.

CHARLES E. NUTTING.
